UNITED STATES PATENT OFFICE.

WILLIAM RUSSELL REDD, OF OAK PARK, ILLINOIS, ASSIGNOR TO THE MORTON SALT COMPANY, OF CHICAGO, ILLINOIS, A CORPORATION OF ILLINOIS.

CARTON-CAPPING MECHANISM.

Application filed December 31, 1921. Serial No. 526,343.

To all whom it may concern:

Be it known that I, WILLIAM RUSSELL REDD, a citizen of the United States, residing at Oak Park, in the county of Cook and 5 State of Illinois, have invented certain new and useful Improvements in Carton-Capping Mechanisms, of which the following is a specification.

The mechanism of the present invention is 10 designed as an attachment to a carton sealing machine of the character employed for the sealing of cartons containing salt or like granular substances. In certain cartons employed for such a purpose, it is customary to 15 provide a small hole or aperture in one end of the carton for the purpose of affording an outlet for the granular contents thereof, so that the user may pour out the quantity desired as occasion may require. In the past 20 it has been customary to manually insert a small metallic cap into the outlet aperture before the carton was placed on the sealer; and the object of the present invention is to 25 provide automatic mechanism for applying such metallic caps, thereby dispensing with the services of several operators and consequently reducing the cost of the filling operation.

The present invention is built onto the 30 sealing and folding mechanism in proper relation to the travelling carrier for the empty cartons and derives the power required for its operation from the same source as that which supplies the power for 35 the sealing machine, but it will be understood in the description of the present invention that only so much of the sealing machine will be illustrated as is needful to afford a full understanding of the nature of 40 the present invention.

In particular the present invention is directed to the hopper which houses a supply 45 of metallic caps, the chute or guide for directing the caps to the capping device, the means for transporting the caps one at a time from the chute to a point adjacent the orifice in the carton, to the means for forcing the cap into said orifice, to the means for arresting the advance of the column of caps 50 during the capping operation, to the safety appliances for operating the machine idly during a cessation in the advance of the procession of cartons and to the other operating

mechanisms for actuating various parts in proper timed relation to one another. 55

In the drawings:

Fig. 1 is a side elevation of the traveling carton carrier of a sealing machine showing the capping mechanism in operative relation thereto and with the hopper partially in 60 section;

Fig. 2 is a sectional fragment of the hopper showing the angular groove for the delivering of the metallic caps taken on line 2-2 of Fig. 1; 65

Fig. 3 is a side elevation of the capping mechanism;

Fig. 4 is a longitudinal sectional elevation thereof showing the capping head in the delivery position, the sectioned portion being 70 taken on line 4 of Fig. 5;

Fig. 5 is a top or plan view of the capping mechanism;

Fig. 6 is a detail of the capping head 75 mainly in section;

Fig. 7 is a perspective view of the end of a carton with its cap inserted;

Fig. 8 is an inner face detail of the guide way for the caps taken on line 8 of Fig. 3;

Fig. 9 is an inner face detail showing the 80 stop pins for arresting the column of caps and the safety mechanism for arresting the active operation of the machine when the advance of the procession of cartons is stopped taken on line 9 of Fig. 3; 85

Fig. 10 is a perspective view showing the 90 guide for the stop arm of such safety appliances; and

Fig. 11 is a perspective detail of the cross head which carries the lowermost stop pin 95 for the column of caps.

The metallic caps 12, which are best illustrated in Figs. 2 and 7, are stamped from sheet metal to provide a circular dished body portion provided with an outwardly extending flange 13 which caps are supplied from a hopper 14 mounted upon a vertical rock shaft 15 journaled at its lower end within a socket head 16 carried by a bracket arm 17 upstanding from the main frame of the machine. 100

The hopper is provided with a conical base plate 18 which terminates slightly short of the cylindrical side wall of the hopper and thereby affords an annular groove or 105 channel 19 of proper width and depth to re-

ceive the caps in edgewise relation as indicated in Fig. 2, but excludes the caps when lying in flatwise relation. Most of the caps in sliding down the conical surface of the 5 base plate will arrange themselves with the flanged or open side down and enter edgewise into the annular groove with the flanged or open side toward the center as indicated by the lower cap in Fig. 2. This 10 is the position which they must occupy in order to be discharged from the hopper and to permit their discharge, the bottom wall 20 of the hopper is provided on one side with a discharge orifice 21 configured to 15 permit only the properly positioned caps to fall through.

In order to effect an agitation of the caps in the hopper the rock shaft 15 is provided with an outstanding crank arm 22 which 20 receives motion from a link 23 eccentrically carried by a disk 24 mounted upon a transmission shaft 25 adapted to receive power from any suitable source. This arrangement serves to impart a short sharp vibratory movement to the hopper which serves to shake the caps and cause them to arrange themselves in edgewise relation within the 25 annular channel. In order to take care of any caps which fall into the channel face 30 out as indicated at the top of Fig. 2, a second orifice 26 like the orifice 21 is provided, but being arranged in opposite relation thereto will prevent the discharge of the properly adjusted caps which can only 35 find exit through the orifice 21.

The mal-adjusted caps falling through the orifice 26 are collected in a box or can 27 from which they may be again poured into the hopper.

10 The orifice 21 registers with a flattened slightly flexible chute 28 the upper end of which vibrates with the hopper, which chute receives the caps in column form and in edgewise relation and conveys them down 15 to a guide-way 29 formed in the face of a vertically disposed guide plate 30 upstanding from a standard 31 (see Fig. 8) which springs from a base plate 32 suitably supported upon the bed 33 of the machine. 20 The front of the guide plate 30 is covered by a closing plate 34 provided in its face with a vertically disposed slot 35 through which the column of caps is exposed as indicated in Fig. 8.

25 The progress of the column of caps is regulated by the means of upper stop pins 36 and the lower stop pins 37 (see Fig. 4) which pins are in vertical alignment with one another and operate in alternation 30 through the vertical slot 35 against the caps which are exposed open side forward to the action of the pins. That is to say, when the lower pin is advanced as indicated in Fig. 4, the entire column is arrested but 35 with the subsequent advance of the upper

pin 36 and the concurrent recession of the lower pin, the lowermost cap will be free to fall through the guide-way until it is engaged by a capping head 38 carried by a swinging arm 39 presently to be described. 70

The pin 36 is carried by an upper cross head 40 (see Figs. 4 and 9) and the pin 37 by a lug 41 depending from a lower cross head 42. The upper cross head is carried by a pair of spaced guide rods 43 and the lower cross head by a similar pair of spaced guide rods 44 (see Figs. 4 and 9), both pairs of guide rods being slidably mounted within a guide block 45 which rests upon and is supported by the center frame 46 of the machine. The upper guide rods at their rear end are connected by a rear upper cross head 47 and the lower guide rods by a similar rear cross head 48, each of which cross heads in its center is provided with a pair of ears 49 between which pairs of ears are mounted anti-friction rollers 50 which bear against upper and lower cams 51 and 52 respectively mounted in opposite relation upon a cam shaft 53, so that as the upper pin is advanced the lower pin will be withdrawn and vice versa. Only the projection of the pins is effected by the cams, the return movements being effected by the action of coil springs 54 which surrounds the guide rods and are interposed between the guide blocks 45 and the respective upper and lower rear cross heads 47 and 48. 90

100 The capping head 38, which is best shown in Fig. 6, is in the form of a cylindrical block of substantially the flange diameter of one of the caps, and the capping head when in raised position presents its flat face vertically to the falling caps which latter 105 are caught by an undercut finger 55 which engages the cap flange at its lower edge. A steel ball 56 protruding from a bore 57 and backed by a spring 58 serves to exert the necessary spring pressure against the forward face of the cap flange to hold the same in engagement with the capping head while the latter is swung down into a position to register with the hole in the carton 110 to be capped. The capping head is carried by a swinging arm 39 (see Fig. 4) which arm is socketed in a swinging block 60 carried by trunnions 61 within a yoke frame 62 the head 63 of which has fitted thereinto a vertical guide stem 64 which passes through the cross head 65 of the main frame 46 and through the guide block 45 being guided therein for vertical reciprocation. 115

120 The sides of the main frame are provided with vertically elongated slots 66 which serve as guides for the reciprocation of the trunnions 61, and the inner trunnion 61, as shown in Fig. 3, has rigidly mounted thereon a disk 67 which carries an eccentrically disposed crank pin 68 carrying an anti-fric- 125 130

tion roller 69 which works in an L-shaped guide slot 70 formed in a guide plate 71 upstanding from the base of the machine as best shown in Figs. 3 and 5. By this arrangement, as the yoke 62 is moved vertically, the roller 69 engaging the L-shaped slot will swing the arm 39 which carries the capping head downwardly from a horizontal to a vertical position.

10 The vertical movement of the yoke is effected by means of a roller 72 which is carried on a stud 73 entered into the rear cross wall 74 of the yoke (see Fig. 4) and disposed at right angles to the upper cross head. The roller is moved vertically by the action of the cam head 75 which carries a peripheral cam flange 76 having an easy cam face 77 and an abrupt cam face 78 as best shown in Fig. 3, which cam head 29 is carried upon the cam shaft 53. This arrangement affords an easy uplifting or return movement to the yoke and the capping head carried thereby and a somewhat abrupt down movement of these parts, 25 which latter is effected by the tension of a pair of springs 79, the upper ends of which are secured to a cross bar 80 carried by the stem 64, the lower ends of the springs being secured to the side walls of the main 30 frame on opposite sides thereof.

In order to insure a positive gripping of the caps by the capping head 38, the caps are forced into engagement thereby by means now to be described. The standard 35 31 which supports the chute, is provided with a vertical slot 81 (see Fig. 4) which slot affords clearance for the action of a finger 82 which is mounted upon a pivot 83 carried by a yoke 84 supported for vertical reciprocation upon the lower end of a stem 85 mounted within a guide lug 86 which projects rearwardly from the standard 31, the upper end of the stem being encircled by a coil spring 87 which bears 40 against a nut 88 to effect a lifting movement 45 of the yoke and parts carried thereby.

The mounting for the finger 82 is provided with a tail piece 89 which is so positioned on its downward movement that it 50 will engage a spring supported stop-pin 90 carried by a lug 91 and to engage an oppositely disposed upper pin 92 on its return movement. The arrangement is such that as the yoke is moved downwardly, the 55 tail piece will be engaged by the lower pin and the finger 82 will be swung downwardly through the slot 81 and against the lowermost cap previously released by the pin 37 thereby positively forcing the cap downwardly and into engagement with the capping head, which positive action is necessary, 60 since gravity cannot safely be relied upon to carry the released cap to the desired position. The up and down movements of the mechanism just described are effected through the

medium of a lever 93 which is pivoted at its rear end to the yoke 84 and is fulcrumed at an intermediate point 94 to the rear side wall of the main frame, being provided at its forward end with an inwardly extending roller 95 adapted to ride upon a cam flange 96 carried by the cam shaft. The pivotal action between the arm 93 and the yoke 84 is designed to afford the necessary lost motion to accommodate the arcuate movement 75 of the lever to the reciprocating movement of the yoke.

When the filled cartons are passing the capping point in uninterrupted sequence, 80 each movement of the capping head will result in the discharge of a cap, but in case the procession of cartons is interrupted, it becomes necessary to provide means for arresting the further down flow of the column of caps. For this purpose, the following mechanism is provided.

The lower cross head 42 at one end thereof is provided with a short depending flange 97 (see Figs. 3, 9, and 11) which terminates short of the depending lug 41 which carries the lower stop pin and behind this flange, when the cross head 42 is advanced, the upper end of a stop lever 98 is adapted to swing. As indicated in full lines in Fig. 9, when the upper end of the lever is 95 stopped in an intermediate position behind the flange 97, it will prevent the retraction of the cross head with its lower pin 37, so that the release of caps in the column will be arrested. In the normal operation of the 100 machine, the stop lever will, on each actuation, swing through its complete arc of movement in timed relation to the advance and recession of the cross head, so that no arresting thereof will be effected.

The inner limit of movement is indicated in dotted lines in Fig. 9 and the outer and inner movement is limited by means of a flanged guide piece 99 carried by a stem 100 entered into the main frame. The stop 110 lever 98 is mounted upon a rock shaft 101 carried by a journal bearing 102 secured to the base of the standard 31 and this rock shaft, at an intermediate position, carries a trip finger 103 which, when the capping 115 head 38 is empty, is designed to freely swing across the face thereof after its return movement without being arrested. If, however, the capping head should return from one of its excursions without discharging its 120 cap, the trip finger will strike the body of the cap held by the capping head and be arrested at such a point as to hold the stop lever 98 in position behind the flange 97 of the cross head 42, so that the latter can- 125 not return to its releasing position.

As shown in Fig. 8, the rock shaft 101 is rocked by means of an actuating arm 104 which is outwardly curved at its upper end 105 and is adapted to be engaged by a bowed 130

spring 106 which is secured to the side of the vertically movable yoke 84, so that each movement of the yoke will serve to impart a corresponding movement to the rock shaft 101 sufficient to effect an out throw of the stop lever 98 to its limit of movement thereby bringing the latter to a position in which it will not obstruct the return movement of the lower cross head. When 10 the yoke 84 is lifted, the rock shaft will be given an inward rotation through the tension of the spring 107 secured to the stop lever 98 (see Fig. 9), and this movement will normally be sufficient to ensure a complete inward swing of the stop lever 98 unless the movement is arrested by the presence of an undischarged cap on the capping head, the swing of these parts being timed to precede the recession of the lower 20 cross head. If the lower stop pin 37 be not released, the finger 82 will strike against an immovable cap so that as the tail piece 89 engages the spring supported lower pin 90 (see Fig. 3) the continued movement of the 25 yoke 84 will result in a depression of the lower stop pin 90 which is spring supported to allow for these conditions.

The cam shaft 53 is provided at its end with a bevel pinion 108 which meshes with 30 a bevel pinion 109 carried by a power shaft 110 journaled in a bracket 111 secured to the base of the machine in any suitable manner and the speed of rotation of the power shaft will be in timed relation to the 35 travel of the carriers which bring the cartons respectively in capping position.

Fig. 1 illustrates the general relation of the capping mechanism to the carton carrying mechanism which latter, however, forms 40 no portion of the present invention and will be but briefly referred to.

Each filled carton is supported upon a carrier 112 mounted upon a suitable conveyor 113 in position to bring the discharge orifice of the carton, at the proper moment, immediately below the capping head when in its lowered position as indicated in Fig. 4. Each carton 113^a is provided with a pair of flaps 114 the rearmost of which, in the line 45 of advance, is provided with an aperture 115 to receive the cap. As the carton approaches the capping mechanism, the forward flap is pressed down by engagement with a shoe 115^a and the rear or apertured flap is pressed down by the action of a swinging arm 116 having a presser finger 117 at its lower end. The arm 116 is carried by a link 118 actuated by a lever 119 the movements of which link are controlled by a 50 roller 120 traveling in a runway 121 on the upper end of a bracket arm 122. The relation of these parts is such that as the lever 119 is swung inwardly, the end of the link 118 will ride upwardly and swing the arm 116 55 with sufficient speed to over-take the ad-

vancing carton and strike down the rear-most flap into the position indicated in dotted lines before the flap reaches the point of engagement with the shoe 115^a. The carton with its flaps folded down will 60 then advance at a predetermined rate of speed to the capping point simultaneously with the down swing of the capping head, so that the body of the cap will engage the aperture in the flap at the proper moment 65 and be drawn forward therewith and released from the capping head by the advance of the carton. The cap, after insertion, is firmly pressed in place by the action of a presser plate 123 at the rear of the machine 70 which is pivoted to a plate 124 and backed by a spring 125.

The operation of the machine may be summarized as follows: The hopper is filled 75 with the caps and the mechanism thrown into operation. A short sharp vibrating movement will be imparted to the hopper so that the caps therein contained will be agitated and caused to slide downwardly in 80 flatwise relation upon the surface of the conical hopper bottom. Most of the caps will lie open face downward upon the conical surface due to the natural tendency of a body to rest upon its larger face. The 85 caps thus positioned will work down into the annular peripheral groove and those which are properly positioned will be discharged in column form into the chute 28 and travel down until arrested by either 90 the upper or lower stop pins which in alternate relation advance to and recede 95 from the stopping position.

As a cap is released by the recession of the lower stop pin the finger 82 will descend 100 and strike down the cap until caught by the finger on the capping head. Simultaneously with these operations the upper stop pin 36 will advance to momentarily arrest the column of caps until the capping head begins 105 to return to its receiving position. A cap clamped to its face will swing downwardly 110 through the action of the roller 69 in the L-shaped groove 70 and the curve is so configured as to give to the capping head a 115 swinging or arcuate movement until it has reached a position immediately above the capping point after which the movement of the capping head terminates in a short straight vertical thrust which is timed to 120 meet the advancing carton at the proper instant of time.

The cap being inserted in the carton will 125 be drawn away from the capping head, and the latter will then be returned to its receiving position. If a carton should be absent at the proper moment, the capping head will swing back still carrying the cap and in these circumstances, the body of the cap will 130 obstruct the free movement of the trip finger 103 so that the stop lever 98 will be arrested.

in position to prevent the return movement of the lower stop finger 37 thereby stopping the down flow of the column of caps through the chute until the procession of cartons again begins to arrive at the capping position. During such period of rest the capping mechanism will operate idly so that no attention from the operator is required.

The capping mechanism is one which 10 may be applied to any kind of a machine which serves to bring the cartons to capping position in regularly timed sequence, and although, defined as a machine for applying caps to cartons, is obviously adapted to apply caps or plugs to any box or sheet which 15 is perforated after the manner of a carton.

The operating mechanisms are all timed by the arrangement of the cams carried by the cam shaft so that perfect timing at a 20 rapid rate is assured. The safety stop mechanism heretofore described prevents any jamming of the machine and insures against a waste of caps when the capping function is suspended for the time being. The machine 25 may be operated without any attention whatsoever save that required in occasionally filling the hopper with caps which need only be filled at comparatively infrequent intervals. The machine is rugged in 30 construction and can be operated at an expenditure of but a slight amount of power and without requiring that the cartons be stopped in their forward travel during the capping operation.

35 I claim:

1. A capping machine comprising a chute 40 adapted to receive a column of caps, a capping head mounted to move from the chute to the capping point and convey caps one at a time to the capping point, stop mechanism 45 adapted to arrest the advance of the column of caps during the capping operation, and safety appliances adapted to be actuated by the presence of an undelivered cap to continue the arresting action of the stop mechanism when the capping head returns to receiving position with an undelivered cap, substantially as described.

2. A capping machine comprising a chute 50 adapted to receive a column of caps, a capping head mounted to swing from the chute to the capping point and convey caps one at a time to the capping point, stop mechanism 55 adapted to arrest the advance of the column of caps during the capping operation, and safety appliances adapted to be actuated by the presence of an undelivered cap to continue the arresting action of the stop mechanism when the capping head returns to receiving position with an undelivered cap, substantially as described.

3. A capping machine comprising a chute 60 adapted to receive a column of caps, a capping head mounted to move from the chute to the capping point and convey caps one at

a time to the capping point, stop mechanism adapted to arrest the advance of the column of caps during the capping operation, and safety appliances adapted to continue the arresting action of the stop mechanism when the capping head returns to receiving position with an undelivered cap, said mechanism being controlled by engagement of a part thereof with said undelivered cap carried by the capping head, substantially as 70 described.

4. A capping machine comprising a chute 75 adapted to receive a column of caps, a capping head mounted to swing from the chute to the capping point and convey caps one at a time to the capping point, stop mechanism 80 adapted to arrest the advance of the column of caps during the capping operation, and safety appliances adapted to continue the arresting action of the stop mechanism when the capping head returns to receiving position with an undelivered cap, said mechanism being controlled by engagement of a part thereof with said undelivered cap carried by the capping head, substantially as 85 described.

5. In a capping machine the combination 90 of a hopper adapted to arrange caps in edge-wise relation, a chute adapted to receive the caps in edge-wise relation from the hopper and convey the same in column form, a capping head mounted to move to receiving position in line with the column of caps and provided with means for engaging and holding 95 a cap in face-wise relation to the capping head, means for forcing the caps into engagement with the head, means for moving the capping head from receiving to capping position, alternately acting stop pins for releasing the column of caps one at a time to position to be engaged by the capping head, and safety mechanism adapted 100 to continue the arresting action of one of the stop pins when the capping head returns to receiving position with an undischarged cap, said mechanism including a member adapted to engage such undischarged cap and thereby bring the mechanism into action, substantially as described.

6. In a capping machine the combination 105 of a hopper adapted to arrange caps in edge-wise relation, a chute adapted to receive the caps in edge-wise relation from the hopper and convey the same in column form, a capping head mounted to move to receiving position in line with the column of caps and provided with means for engaging and holding 110 a cap in face-wise relation to the capping head, means for forcing the caps into engagement with the head, and means for moving the capping head from receiving to capping position, the cap engaging means being adapted to permit the removal of a cap from the capping head by the continued advance of the capped article, alter- 115

nately acting stop pins for releasing the column of caps one at a time to position to be engaged by the capping head, and safety mechanism adapted to continue the arresting action of one of the stop pins when the capping head returns to receiving position with an undischarged cap, said mechanism including a member adapted to engage such undischarged cap and thereby bring the mechanism into action, substantially as described.

7. In capping mechanism the combination of a guide for the caps, a swinging capping head adapted when in receiving position to register with the cap guide and provided with a hooked finger adapted to engage one edge of a cap and hold the cap in face-wise relation to the capping head, and means for swinging the capping head from receiving to discharging position, substantially as described.

8. In capping mechanism the combination of a guide for caps, a capping head, a mounting for the capping head provided with trunnions, a vertically movable yoke through which the trunnions are journaled, means for vertically moving the yoke, means for turning the trunnions and swinging the capping head concurrently with the vertical movement of the yoke to carry the capping head from a position registering with the cap guide to the capping position, alternately acting stop pins adjacent the cap guide for controlling the passage of caps therethrough in timed relation to the movements of the capping head, a safety mechanism adapted to hold the stop mechanism in stopping position when the capping head returns to receiving position with an undischarged cap, said mechanism including a member adapted to engage with such undischarged cap on the capping head, substantially as described.

9. In capping mechanism the combination of a guide for caps, a capping head, a mounting for the capping head provided with trunnions, a vertically movable yoke through which the trunnions are journaled, means for vertically moving the yoke, means for turning the trunnions and swinging the capping head concurrently with the vertical movement of the yoke to carry the capping head from a position registering with the cap guide to the capping position means for forcing the caps one at a time into engage-

ment with the capping head when in receiving position, alternately acting stop pins adjacent the cap guide for controlling the passage of caps therethrough in timed relation to the movement of the capping head, a safety mechanism adapted to hold the stop mechanism in stopping position when the capping head returns to receiving position with an undischarged cap, said mechanism including a member adapted to engage with such undischarged cap on the capping head, substantially as described.

10. In capping mechanism the combination of a capping head, a mounting therefor, trunnions on the mounting, a yoke through which the trunnions are journaled, means for reciprocating the yoke, a member carried eccentrically by one of the trunnions, and a member provided with a slot for engaging said eccentrically mounted member to impart rotation to the trunnions and a swinging movement to the capping head as a resultant of reciprocating movements imparted to the yoke, substantially as described.

11. In a capping machine the combination of a guide for caps, a movable capping head adapted to transport caps from the guide to the capping point, means for forcing the caps one at a time into engagement with the capping head, said means comprising a pivoted finger and a reciprocable mounting therefor, the finger being positioned to strike down the caps within the guide-way and being provided with a tail piece and a member adapted to be engaged by said tail piece and to effect a movement of the finger, substantially as described.

12. In a capping machine the combination of a guide for caps, a capping head movable from receiving position in register with the guide to capping position, slidably mounted upper and lower stop fingers for controlling the progress of caps through the guide, a swinging stop member adapted normally to swing back and forth to position to clear the mounting for one of the stop fingers, and means associated with said swinging member and adapted to engage with an undelivered cap carried by the capping head on its return movement and by such engagement to arrest the swinging stop member in position to prevent movement of the stop pin, substantially as described.

W. RUSSELL REDD.
